UNITED STATES PATENT OFFICE.

GEORGE W. CAMPBELL, OF HARTFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed November 22, 1922. Serial No. 602,509.

The present invention relates to means, in a typewriting machine, for locking the platen-carriage, platen case-shift frame and other movable parts against displacement on the main frame, preliminary to enclosure of the machine in a casing. The invention more particularly relates to machines of the so-called portable class.

The casing for a portable machine ordinarily fits the machine so snugly as to require the carriage to be centered on the main frame and the case-shift frame to be set in lower-case position. Furthermore, unless these parts are locked against play, the machine may be injured in the transportation thereof in its casing. Even when the carriage has been centered by a locating device, a blow on the casing has not infrequently caused the teeth of the carriage-rack or its drive-pinion to be stripped.

Ordinarily, in the operation of the machine, the carriage-rack is releasable from its drive to permit the carriage to be moved freely by hand or to be jumped by the drum-spring; and an object of the present invention is the provision of means for holding the carriage-rack disengaged from its drive when the machine is in its casing, so that blows on the casing may not result in injury to the driving, or other connections, of the carriage.

An object of the invention is the provision of a simple, inexpensive device, operable with ease and certainty, which functions not only to locate and hold the carriage, but also to hold the carriage-rack disengaged from its drive.

A further object of the invention is the provision of means, on such a carriage and carriage-rack-holding device, for locking the case-shift frame against play.

A feature of the invention is the provision of a device on the case-shift frame for locking the latter to the main frame, and for centering and holding the carriage when thrown to such locking position.

Another feature of the invention is a combined carriage-locator, case-shift-frame lock, and carriage-rack-holding device which may be made of a single piece of sheet-metal

formed in one or more stamping or bending operations, and which may require only a pivot screw or pin for its attachment to the machine.

Other features and advantages will hereinafter appear.

In the accompanying drawings,

Figure 1 is a view, in side elevation, of the platen-carriage and a part of the shift-frame and main frame, with the locking and holding device of the invention in its normal or ineffective position, for typewriting.

Figure 2 is a view similar to Figure 1 except that the locking and holding device of the present invention is shown in effective position, with the carriage and shift-frame held against movement and the letter-feed rack held out of engagement with its drive-pinion.

Figure 3 is a view, in front elevation, of the structure shown in Figures 1 and 2.

Figure 4 is a front, detail view of the locking and holding device; the same being in its normal or ineffective position, below the path of the carriage.

Referring to Figure 1, the platen 10 is shown as on an axle 11, journaled in the side plates 12 of the platen-carriage. The side plates 12 are connected at their lower edges by a cross-piece 13; the forward portion of which is supported by ball-bearings 14 on a rail or cross-piece 15, forming part of the shift-frame. The upper rear portion of the carriage is supported, by means of rollers (not shown), on a rail (not shown), on the shift-frame. The carriage is, therefore, mounted for easy movement in letter-feed and return directions on the shift-frame, whatever the case-shift position of the latter may be. The shift-frame, with the carriage thereon, is movable up and down between case-positions by means of shift-key levers and connections (not shown), but which are well understood in the art, and, for a fuller disclosure of which, reference may be made to United States Letters Patent to William A. Dobson, No. 1,335,956, granted April 6, 1920.

The carriage is urged in letter-feed direction by the usual spring-drum (not

shown); the feed of the carriage under the impulse of the spring-drum being controlled by means well known in the art. Briefly, this means comprises a rack 17 on the carriage, adapted to engage a pinion 18, journaled on the shift-frame; the pinion 18 having fast thereto a ratchet-wheel 19, controlled by a dog-rocker (not shown); which dog-rocker is actuated through a universal bar, by the keys, to permit of step-by-step movement of the ratchet-wheel 19, pinion 18 and rack 17, with the carriage, as the keys are actuated in the typewriting operation. When the carriage is to be returned to the beginning of a line, or is to be moved in counter-letter-feed direction, against the action of the spring-drum, the rack 17 is released from the pinion 18. To permit of such release of the rack, the same is carried by arms 20, one at each side of the machine, and journaled on pins 21, set into the side plates 12 of the carriage. The arm 20 at the right-hand side of the machine is shown as being one arm of a bell-crank, the other arm 22 of which terminates in a boss 23, which is received in a yoke 24 on one arm 25 of a lever pivotally mounted on the axle 11. The rearward arm 26 of this lever terminates in a finger-piece 27, which, upon being depressed, causes the arm 22 of the bell-crank to be rocked forward and the rack-carrying arms to be rocked upward to lift the rack 17 out of engagement with the pinion; thereby releasing the carriage to the action of the spring-drum.

For effecting line-feed, rotary movement, of the platen, the axle 11 thereof may be provided, at its right-hand end, with the usual hand-knob 28, and, at its left-hand end, with line-space mechanism of the usual character. This line-space mechanism may comprise a ratchet-wheel 29, fast to the platen-axle, a pawl 30, for engagement with the ratchet, a slide 31, on which the pawl is mounted, and a bell-crank lever, pivoted to a bracket 32 on the left-hand side plate 12 of the carriage; the bell-crank lever comprising an arm 33, which connects to and operates the pawl-carrying slide, and a forwardly-extending arm terminating in a finger-piece 34.

The mechanism thus far described is not new with the present invention, but is that found on the Underwood standard portable typewriter.

The locking and holding mechanism of the present invention is as follows. Pivoted at 35 to the front cross-piece 15 of the shift-frame is an arm or rocker 37. From its pivot 35, this arm has a downward bend 38, to bring the same below the cross-piece 15. Thence it extends forwardly, at 39, to a bend 40, to bring it behind the bar 15. It is thence extended toward the left, as indicated at 41.

At its left-hand end, the arm or rocker 37 has a rearward offset or plate 42 which may be conveniently utilized as a finger-piece for operating said arm. From the upper edge of this offset or plate 42, a finger or detent 43 is turned substantially horizontally to the right.

When the arm 37 is in its Figure 4 position, the finger 43 is below the level of the lower edges of the side plates 12 of the carriage, so that the carriage may move freely to the left beyond the finger 43. When, however, the plate or offset is seized and lifted in such manner as to rock the arm 37 upward around its pivot 35, the finger 43 is interposed in the path of movement of the left-hand end plate 12 of the carriage; and, if the arm 37 is rocked to the correct elevation, the finger 43 thereon will register with, and be received in, a recess 44 in the carriage-side plate. The plate 42 and finger 43 on the rocker, therefore, in the upper position of the same, serve to prevent leftward movement of the carriage beyond the same, and, in fact, are so positioned as to arrest the carriage in center position in respect to the main frame of the machine. The engagement of the finger 43 in the hole or recess 44 in the carriage-side plate prevents return of the rocker or locking device to its normal or ineffective position.

The plate or rearward offset 42 of the arm 37, in addition to the finger 43 at the upper edge thereof, has, at its lower edge, a rightward offset 45 (see Figure 4), which is continued into a downward offset or ear 46. On the lower end of the ear 46 is a flange or tooth 47, offset to the left. When the rocker is swung from its ineffective, Figure 4, position to its Figure 3 position, the flange or tooth 47 moves upward, and to the left, until it engages under, and is arrested by, a flange 48 on the side plate 49 of the main frame of the machine. This flange 48 is ordinarily present on the Underwood standard portable machine as heretofore marketed. In the position in which the rocker is arrested by engagement of the flanges 47 and 48, the finger 43 at the top of the plate 42 is in alignment or registration with the hole 44 in the side plate 12 of the carriage; that is to say, if the rocker be held up by the finger, with the flanges 47 and 48 in contact, and the carriage be released by the finger-piece 27 and allowed to travel to the left, under control of the hand, the finger 43 would be received in the hole 44. It has been stated that the finger 43 is directed substantially horizontally rightward. Preferably this finger is at a slight upward incline, so that, as the carriage presses to the left, the under face of the finger 43 acts as a cam to exert an upward pressure on the rocker and to crowd and hold the flange 47 to the

flange 48 in such manner that the rocker may not be sprung or knocked from its effective position.

Even though the carriage were held 5 against leftward movement on the shift-frame by means of the plate 42 and finger 43, the shift-frame, together with the carriage, would be movable between case-positions except for the engagement of the flange 10 47 of the rocker with the flange 48 of the main frame of the machine. This latter engagement locks the shift-frame down in lower-case position on the main frame. The carriage, although free to have movement in 15 letter-feed and return directions on the shift-frame is, nevertheless, by means old in the art, held against movement upward with respect to the shift-frame. Consequently, when the shift-frame is locked 20 down by the flanges 47 and 48, the carriage is also locked down. The rocker 37, therefore, serves the double function of holding the carriage centered and of locking the carriage and shift-frame against case-shift movement, that is, of clipping the carriage and shift-frame to the main framework, the 25 jaws of the clip being 43 and 47.

The rocker 37 has the further function, hereinbefore mentioned, of holding the carriage-rack 17 out of engagement with its driving pinion 18 when the parts are locked for placement of the machine in its casing. To this end, the plate or offset 42 of the rocker has a third tongue or finger 50, turned 30 at a rightward and rearward incline, from the rear edge thereof, to cross the path of movement of the carriage-rack with the carriage. When the rocker is in its normal, Figure 4, position, this finger 50 is below the carriage-rack 17, and the latter may move freely with the carriage thereover. Upon movement of the rocker to Figure 3 position, however, the finger 50 is brought into the path of movement of the rack 17. Even with the rocker in Figure 3 position, however, the rack 17 may not be moved with the carriage into engagement with the finger 50, because such movement of the carriage and rack to the left can only be had when the rack-releasing finger-piece 27 is depressed, and when the rack is therefore, elevated. The elevation of the finger 50 in the Figure 3 position of the rocker is not sufficient to permit of contact of the rack with the rocker in the movement of the rack with the carriage to the left while the finger-piece 27 is held depressed. Consequently, the finger 50 will not interfere with movement of the rack and carriage leftward to a position for engagement of the rocker-finger 43 in the hole 44 of the carriage-side plate. At the time of such engagement of the finger 43 in the hole 44, the left-hand end of the rack is, however, over the finger 50; and, if at this time the finger-piece 27 is released, the rack, instead 55 60 65 70 75 80 85 90 95 100 105 110 115 120 125 130

of dropping back into engagement with the pinion, falls upon the finger 50 and is held by the latter up, out of engagement with the pinion. A spring (not shown) is ordinarily employed to insure return of the rack 17 in to engagement with the pinion 18 whenever the finger-piece 27 is released. Such spring, however, is ineffective to force down the rocker-finger 50, and rocker, to ineffective position, because the finger 43, being in the hole 44 in the side plate of the carriage, is held by the latter and holds the rocker up against any pressure of the rack on the finger 50.

The casing ordinarily fits the typewriter in such manner that movement of the carriage to the right is arrested by engagement of the knob 28 either with the wall of the casing or with a pad or block thereon. When, therefore, the machine is locked, as hereinbefore described, and placed in its casing, movement of the carriage to the right to an extent sufficient to cause the same to be withdrawn from the rocker-finger 43 is impossible. Upon removal of the machine from the casing, however, the parts may be released by a simple movement of the carriage to the right. Once the carriage is clear of the finger 43, the rocker will drop by gravity to its ineffective, Figure 4, position. In fact, the pressure of the carriage-rack on the rocker, after the finger 43 is released from the carriage, will ordinarily be sufficient to throw the rocker to ineffective position if the same fails to drop by gravity. A spring (not shown) may, however, be employed for the specific purpose of returning the rocker to its ineffective, unobstructing position when the same is released from the carriage by a rightward movement of the latter.

The rocker is preferably of a single sheet-metal stamping, bent or formed in one or more operations. In the formation thereof, it may have a strengthening bead, such as indicated at 51, formed therein, and this bead may, as indicated in Figure 3, extend downward on the plate-portion 42 and rightward along the lower offset or finger 45. The locking and holding device, per se, is, therefore, inexpensive, both as to the material thereof and the cost of manufacture. Its only attachment to the machine being its pivot-screw 35, it is easily placeable and replaceable if injured, and involves no modification of the standard structure, or additions thereto other than the rocker itself.

It is to be understood that certain features of the invention are not limited to use with a case-shifting mechanism.

Variations may be resorted to within the scope of the invention, and portions of the improvements may be used without others.

Having thus described my invention, I claim:

1. In a typewriting machine, a platen, a main frame, a case-shift frame thereon, a platen-carriage movable in letter-feed and return directions on the case-shift frame, and a one-piece normally-ineffective locking device mounted for movement on the case-shift frame and shiftable to engage the main frame for holding the case-shift frame against movement, and to engage the platen-carriage to hold the latter against movement on the case-shift frame.

2. In a typewriting machine, a platen, a main frame, a case-shift frame thereon, a platen-carriage movable in letter-feed and return directions on the case-shift frame, and a one-piece normally-ineffective locking device mounted for movement on the case-shift frame and shiftable to engage the main frame for holding the case-shift frame against movement, and to engage the platen-carriage to hold the latter against movement on the case-shift frame, said locking device automatically releasable by movement of the carriage to the right.

3. In a typewriting machine, a platen, a main frame, a case-shift frame thereon, a platen-carriage movable in letter-feed and return directions on the case-shift frame, and a one-piece arm pivoted to the case-shift frame, said arm including a finger for engagement with the main frame to lock the case-shift frame, and a second finger on the arm interposable into the path of movement of the platen-carriage to hold the latter against movement to the left on the case-shift frame, said arm automatically releasing itself by its own weight upon movement of the carriage to the right.

4. In a typewriting machine, a platen, a main frame, a case-shift frame thereon, a platen-carriage movable in letter-feed and return directions on the case-shift frame, and a one-piece arm pivoted to the case-shift frame and having a finger for engagement with the main frame to lock the case-shift frame, and a second finger interposable into the path of movement of the carriage to hold the latter against movement on the case-shift frame; the carriage having a recess at one end therein to receive an offset of the last-mentioned interposed finger when the carriage abuts such finger to hold the arm in its effective position.

5. In a typewriting machine, a platen, a shift-frame, a platen-carriage movable in letter-feed and return directions, a rack on the carriage, a pinion for driving the rack and carriage, means for disconnecting the rack and pinion, and a single one-piece locking device on the shift-frame settable to hold the rack and pinion disconnected.

6. In a typewriting machine, a platen, a shift-frame, a platen-carriage movable in letter-feed and return directions, a rack on the carriage, a pinion for driving the rack

and carriage, means for disconnecting the rack and pinion, and a single one-piece locking device on the shift-frame settable to hold the carriage against movement and to hold the rack and pinion disconnected.

7. In a typewriting machine, a platen, a shift-frame, a platen-carriage movable in letter-feed and return directions, a rack on the carriage, a pinion for driving the rack and carriage, means for disconnecting the rack and pinion, and a single one-piece locking device on the shift-frame shiftable to engage the carriage, upon release of the rack from the pinion, to hold the carriage against movement and to prevent re-engagement of the rack with the pinion while the carriage is so held.

8. In a typewriting machine, a main frame, a platen, a platen-carriage movable in letter-feed and return directions, a rack on the carriage, a pinion for driving the rack and carriage, means for disconnecting the rack and pinion, a case-shift frame, and a normally-ineffective one-piece locking device mounted on the case-shift frame and settable to lock the case-shift frame and hold the rack and pinion disconnected.

9. In a typewriting machine, a platen, a platen-carriage movable in letter-feed and return directions, a carriage-drive, means for breaking the drive, a case-shift frame, and a normally-ineffective locking device shiftable on the case-shift frame for engagement with the carriage to hold the same against movement, the case-shift frame locked, and the carriage-drive broken.

10. In a typewriting machine, a main frame, a platen, a case-shift frame, a platen-carriage movable in letter-feed and return directions on the case-shift frame, a rack on the carriage, a pinion on the case-shift frame for driving the rack and carriage, means for disengaging the rack from the pinion, and a device on the case-shift frame movable to lock the latter to the main frame, and having extensions thereof, one of which, when the device is so moved, is interposed in the path of the carriage to serve as a stop therefor, and another of which concomitantly obstructs and prevents re-engagement of the rack with the pinion.

11. In a typewriting machine, a main frame, a platen, a case-shift frame, a platen-carriage movable in letter-feed and return directions on the case-shift frame, a rack on the carriage, a pinion on the case-shift frame for driving the rack and carriage, means for disengaging the rack from the pinion, a device on the case-shift frame movable to lock the latter to the main frame, and having extensions thereof, one of which, when the device is so moved, is interposed in the path of the carriage to serve as a stop therefor, and another of which concomitantly obstructs and prevents re-engagement of the rack with the pinion.

rack with the pinion, and means whereby the carriage holds said device locked to the main frame.

12. The combination with a typewriting machine having a carriage and a shift-frame whereon it travels, of a normally-ineffective lock stationary with respect to the shift-frame and shiftable to position to prevent advance of the carriage to the left, and a 10 transportation casing for said machine, comprising a cover, which fits over the carriage and acts as a stop against movement of the carriage to the right, said lock releasable by movement of the carriage to the right after 15 the cover is removed.

13. The combination with a typewriting machine having a carriage and a shift-frame whereon it travels, of an arm mounted on the shift-frame and normally in ineffective 20 position, said arm provided with a stop, the arm being shiftable to cause the stop to engage the carriage to lock the carriage against advance to the left, a transportation casing for said machine, comprising a cover, 25 which fits over the carriage and acts as a stop against movement thereof to the right, and means upon said arm to lock the shift-frame, said arm releasable by movement of the carriage to the right after the cover is 30 removed.

14. The combination with a typewriting machine having a shift-frame and a carriage movable in letter feed and return directions on the shift-frame, a rack on the carriage, a 35 pinion for driving the rack and carriage, and means for disengaging the rack from the pinion, of a normally-ineffective lock stationary with respect to the shift-frame, said lock shiftable to position to prevent 40 advance of the carriage to the left and effective to disengage the rack from its driving pinion, and a transportation casing for said machine, comprising a cover, which fits over the carriage and acts as a stop against movement 45 thereof to the right, said lock effective to automatically release itself and permit the rack to re-engage its driving pinion upon movement of the carriage to the right after the cover is removed.

50 15. In a portable typewriting machine, in combination, a platen, a letter-feeding carriage, escapement-mechanism therefor, a case-shifting frame, a normally ineffective locking device movable to position to lock 55 the case-shifting frame against shifting, also to release the carriage from the escapement-mechanism and to prevent the carriage from being moved in one direction, and a machine-transporting casing which maintains 60 the locking device engaged, said locking device including a part which is engaged by the carriage to maintain the lock effective, and which is automatically released upon movement of the carriage in the opposite direction after removal of the casing.

16. In a portable typewriting machine, a main frame, a platen, a letter-feeding platen-carriage, escapement-mechanism therefor, a case-shifting frame, a single finger-piece, means normally ineffective but operable by 70 a movement of said finger-piece to position to lock said case-shifting frame against shifting and for locking the platen-carriage against advance movement, and also to release the carriage from the escapement-mechanism and arrest it in central position, and a casing for carrying said machine and engaging with said carriage for preventing movement of the carriage in the opposite 75 direction and for locking the finger-piece in 80 effective position.

17. In a portable typewriting machine, a main frame, a platen, a letter-feeding platen-carriage, escapement-mechanism therefor, a case-shifting frame, a single finger-piece, 85 means normally ineffective but operable by a movement of said finger-piece to position to lock said case-shifting frame against shifting and for locking the platen-carriage against advance movement, and also to release the carriage from the escapement-mechanism and arrest it in central position, and a casing for carrying said machine and 90 for preventing movement of the carriage in the opposite direction, said locking means including a part which is engaged by the carriage to maintain the lock effective, and which is automatically released by movement of the carriage in the direction opposite to letter-feeding after the casing is 95 removed.

18. In a typewriting machine, the combination of a main framework, a carriage, a case-shift frame, a device normally disengaged from the framework but movable to 100 position to clip the carriage and case-shift frame to the framework, and an escapement mechanism for said carriage including a carriage-release member, said clip-device having means to intercept said carriage-release 105 member and hold it in releasing position.

19. In a typewriting machine, the combination of a main framework, a carriage, a case-shift frame, a device normally disengaged from the framework but movable to 110 position to clip the carriage and case-shift frame to the framework, and an escapement mechanism for said carriage including a carriage-release member, said clip-device having means to intercept said carriage-release 115 member and hold it in releasing position, and means supporting said clip-device to enable it to prevent movement of said carriage in letter-feeding direction.

20. In a typewriting machine, the combination of a main framework, a carriage, a case-shift frame, a device normally disengaged from the framework but movable to 120 position to clip the carriage and case-shift frame to the framework, and an escapement 125 mechanism for said carriage.

mechanism for said carriage including a carriage-release member, said clip-device having means to intercept said carriage-release member and hold it in releasing position, 5 means supporting said clip-device to enable it to prevent movement of said carriage in letter-feeding direction, and a machine-cover holding the carriage against retrograde movement and thereby preventing the carriage from being released from the control of said clip-device.

21. In a typewriting machine, the combination with a framework, a releasable carriage and a shift frame, of a part upon said carriage, a catch co-operable with the framework and normally idle, said framework-catch movable to position to present it to said carriage-part as the released carriage advances, means to enable said framework-catch to co-operate with said carriage-part to maintain the carriage released and to hold the carriage from advancing and the shift frame from shifting, and a cover restraining said carriage against retrograde movement.

22. In a portable typewriting machine, in combination, a platen, a letter-feeding platen-carriage, a case-shifting frame, a normally ineffective locking device movable to 30 position to lock the case-shifting frame against shifting and also to prevent movement of the carriage in one direction, and a machine-transporting casing which prevents the retraction of the carriage, said locking device having a detent which coacts with the carriage to maintain the lock in effective position, said detent being automatically releasable upon retraction of the carriage after removal of the casing, and the lock being self-returning after the release of said detent.

23. In a typewriting machine, in combination, a platen-carriage movable in letter-feed and return directions and having a hole in its left end, an arm displaceably mounted on said machine, so as to be normally free of said carriage, an upwardly-extending member on the left end of said arm, and a lateral rightwardly-extending finger on said member, said arm being swingable upwardly to cause said member to engage against the left end of said carriage and said finger to engage in the hole in the left end of said carriage when the latter is moved leftwardly to be centered on said machine preparatory to placing said machine in a carrying case, said finger being disengaged from said carriage on movement of the latter to the right, whereby said arm may be restored to its 50 normal inoperative position.

24. In a typewriting machine, the combination with a platen-carriage movable in letter-feed and return directions and an escapement-mechanism, of an arm displace-

ably mounted on said machine and normally 65 disengaged from said carriage and arranged to be swung upwardly for engaging the left end of said carriage and arresting the leftward movement of the latter when it is centered on said machine preparatory to placing said machine in a carrying case, and a 70 rightwardly-extending member on said arm effective to hold said platen-carriage and said escapement-mechanism in disengaged relation while said arm engages said carriage, said arm being disengaged from said carriage upon movement of the latter to the right.

25. In a typewriting machine, in combination, a platen-carriage, and a device for 80 locking said carriage against leftward movement preparatory to placing said machine in a transporting case, said device including a pivoted arm on said machine fixed against lateral movement and normally disengaged 85 from said carriage, said arm being movable into the path of said platen-carriage-frame for arresting the leftward movement of the latter when it is centered on said machine, a rightwardly-extending finger on said arm, 90 and means carried by said carriage engaging said finger to maintain said arm in operative position.

26. In a portable typewriting machine, in combination, a platen, a platen-carriage-frame supporting said platen and having an aperture in its left end, a transporting case arranged for enclosing said machine, so as to prevent movement of said platen and said frame leftwardly, and a device for locking 100 said frame against leftward movement while in said case, said device including a pivoted arm on said machine fixed against lateral movement and normally disengaged from said frame, a member on said arm arranged 105 to be moved into the path of said platen-carriage-frame for arresting the leftward movement of the latter when it is centered on said machine, and a rightwardly-extending finger on said member engaging in said 110 aperture, said arm being locked in operative position by said finger as long as said case encloses said machine.

27. In a typewriting machine, the combination with a platen-carriage movable in 115 letter-feed and return directions, of an instrumentality displaceably mounted on said machine, so as to be normally free of said carriage and movable to a position for engaging the left end of said carriage and arresting the leftward movement of the latter when it is centered on said machine preparatory to placing said machine in a carrying case, and releaseable from said engagement by moving the carriage to the right from its 120 engaged position with said instrumentality.

28. The combination with a typewriting machine having a carriage and a shift-frame

whereon it travels, of an arm mounted on the shift-frame and normally in ineffective position, said arm provided with a stop thereon, the arm being shiftable to cause the stop to engage the carriage to prevent advance of the carriage to the left, and the stop being releasable from said engagement with the

carriage by moving the carriage to the right from said engaged position, and a transportation casing for said machine, comprising a 10 cover, which fits over the carriage and acts as a stop against movement thereof to the right.

GEORGE W. CAMPBELL.
